UNITED STATES PATENT OFFICE.

BENJAMIN HANN, OF SANTA FÉ, OKLAHOMA TERRITORY.

SHINGLE-GAGE.

SPECIFICATION forming part of Letters Patent No. 521,112, dated June 5, 1894.

Application filed January 18, 1894. Serial No. 497,260. (No model.)

To all whom it may concern:

Be it known that I, BENJAMIN HANN, a citizen of the United States, residing at Santa Fé, in the county of K and Territory of Oklahoma, have invented a new and useful Shingle-Gage, of which the following is a specification.

My invention relates to an improved shingle-gage; and it has for its object the production of a device to be applied to the outer edge of a lathing-hatchet or other suitable implement to serve as a gage for the workman while laying shingles on a roof.

The invention will first be described in connection with the accompanying drawings, and then pointed out in the claim.

Figure 1 is a perspective view of a lathing-hatchet having my improved gage applied thereto. Fig. 2 represents a blank from which the gage is formed. Fig. 3 is a perspective view of the completed gage. Fig. 4 illustrates the manner of using my shingle-gage.

Referring to the drawings, A represents the shank of the gage, which is preferably tapered, having at its lower end a rectangular bifurcated extension B, considerably wider than the lower end of the shank. This extension is bent, on the dotted line Fig. 2, at a right angle to the shank, thus forming shoulders s on each side of the bifurcation b, as shown. In the upper portion of the shank there is formed a series of holes c, through which the gage may be adjustably attached to the implement.

In the drawings I have shown the gage applied to a lathing-hatchet H, having a handle h, a screw d being passed through one of

the holes in the shank and into the end of the handle, the bifurcation in the extension being astride of the edge, as clearly shown in Fig. 1. 40

In using my gage, after the first course of shingles is laid, which is done by a line or any other means, the shoulder s is placed against the lower edge of the shingle in the course below the one about to be laid, and 45 the lower edge of the shingle being laid is placed against the pole or head of the hatchet. By this means the courses of shingles can be laid perfectly true and at equal distances from each other. As the gage is, by means 50 of holes c, capable of being adjusted at different distances from the pole of the hatchet, it will be apparent that the gage will serve to lay a course at any distance from the one last laid. 55

Having thus described my invention, what I claim as new, and desire to secure by Letters Patent, is—

In combination with a hatchet provided with a handle a shingle-gage comprising a 60 shank having a series of vertically-arranged holes in its upper end, a bifurcated right-angled extension at its lower end, said extension being wider than the lower end of the shank, and a screw passed through one of said holes 65 and into the handle, the bifurcation being astride of the edge of the hatchet.

In testimony that I claim the foregoing as my own I have hereto affixed my signature in presence of two witnesses.

BENJAMIN HANN.
